UNITED STATES PATENT OFFICE.

ELIZABETH M. ADAMS, OF PORTLAND, OREGON.

WAIST AND SKIRT SUPPORTER.

SPECIFICATION forming part of Letters Patent No. 680,106, dated August 6, 1901.

Application filed May 11, 1901. Serial No. 59,844. (No model.)

To all whom it may concern:

Be it known that I, ELIZABETH M. ADAMS, a citizen of the United States, residing at Portland, in the county of Multnomah and State 5 of Oregon, have invented a new and useful Waist and Skirt Supporter, of which the following is a specification.

This invention relates to skirt-supporters, and more particularly a skirt-supporter adapted to be used either in connection with an ordinary waist and skirt or with a basque and skirt.

The object is to present a neat and efficient form of skirt-supporter which shall be exceedingly simple in construction, of high efficiency in use, easy of attachment to and detachment from garments, that will not in use be liable to become detached, and that may be manufactured and sold at small cost.

20 The salient features of my invention are, first, simplicity of construction, being made of sheet metal stamped to an appropriate shape and provided with an efficient means to attach it to a garment, and further, while 25 the parts composing the supporter are readily and easily brought into locking engagement with each other accidental separation or detachment of the parts in use will be practically obviated.

30 Another salient feature is that by the material employed in the construction of the parts of the supporter damage to a garment, as from rust, will be prevented, the material employed to combine lightness, non-corrosive 35 qualities, and requisite strength.

Generally stated, my invention resides in a waist and skirt supporter comprising two members, a hook and an eye, each the counterpart of the other with regard to general aspect of shape. The members are constructed 40 of sheet metal, preferably of aluminium on account of its well-known non-corrosive qualities, its extreme lightness, and its great strength, and are stamped up by suitable dies 45 to the required shape. In the case of the hook member the hook portion is stamped to form a shoulder against which a side of the eye member will bear when the parts are assembled, the hook to overlap the eye member 50 and to hold such relation thereto as while not presenting an obstruction to the assemblage of the two members it will prevent ac-

idental separation of the two when in use. Each member is provided with an offset, forming a shield for the pointed end of a pin, the 55 pin to be substituted as a means for holding the members in position on the garment for the ordinary thread or sewed connection, this latter being objectionable on account of the danger of the threads becoming cut and of 60 the supporter separating from the garment when most needed, and also for the further reason that without the expenditure of considerable time and labor the supporter cannot be changed from one garment to another. 65 The pin is bent upon itself one or more times to form a coil, presenting what is known as a "safety-pin," and has one of its members secured to the plate of the hook member and of the eye member in any suitable manner, preferably by forming each of the plates with a tubular rib or offset in which the arm of the pin 70 may be secured in any suitable manner, as by clamping or soldering, or both, the pin by preference to be made of metal that will have 75 sufficient rigidity to bear the strain of the weight of the garment. By preference the pin may be made of steel heavily nickelized or silver-plated to prevent rusting.

While the supporter, as will hereinafter appear, is of an exceedingly simple construction, it will be found to fulfil a long-felt want by reason of its adaptability to position, its high efficiency in use, and certainty and positiveness with which the parts are held in 85 locked engagement under use.

Further and more specific details of construction will be hereinafter more specifically pointed out.

In the accompanying drawings, forming a 90 part of this specification, and in which like numerals of reference indicate corresponding parts, I have illustrated a form of embodiment of my invention capable of carrying my ideas into effect, it being understood that 95 other forms of embodiments thereof may be employed without departing from the spirit thereof, and in these drawings—

Figure 1 is a view in elevation displaying the manner in which the skirt-supporter is 100 applied for use, the figure exhibiting an ordinary waist and skirt with the eye member of the supporter secured to the waist and the hook member secured to the skirt. Fig. 2 is

a view in elevation of the hook member. Fig. 3 is a view in vertical section taken on the line 3-3 of Fig. 2 and looking in the direction of the arrow. Fig. 4 is a view in elevation of the eye member. Fig. 5 is a view in vertical section taken on the line 5-5 of Fig. 4 and looking in the direction of the arrow. Fig. 6 is a vertical sectional view through the two members, showing the co-operative relation between the parts when in locked engagement.

Referring to the drawings, 1 designates the hook member of the supporter, and 2 the eye member. The hook member is stamped up from a sheet of metal and is provided on one side with a hook 3 and with an offset or shoulder 4, the same being, preferably, straight, or, if preferred, it may be slightly incut, so that when the eye is in engagement with the hook, 15 as indicated by dotted lines in Fig. 3, the side of the eye will bear against this shoulder and will be prevented in an appreciable manner from riding toward the hook, and thus become liable to disengagement therefrom. To 20 effect a positive coaction between the eye and the shoulder 4, the hook 3 extends some distance beyond the shoulder and is curved down close to the shoulder, as shown in Fig. 3, so that should the side of the eye ride loose 25 from the shoulder 4 it will by contact with the hook immediately be forced back to its normal position. The plate or side opposite the hook is cut away, leaving at one end an extension 5, which is curved upon itself to form 30 a shield 6 for housing the pointed member of the pin 7, the other member 8 of the pin being housed in a tubular rib 9, formed by bending a portion of the metal at the cut-away side of the hook member to inclose the member 8 35 of the pin. The portion of the pin within the tubular rib may be serrated, or roughened, and under the pressure of the rolls or other means for turning in the rib these serrations may be caused to bite into the inner face of 40 the rib, or the frictional contact between the tubular rib and the member of the pin may be depended on to effect a stable union between these parts or solder may be employed for the purpose. The eye member 2 has the 45 pin secured thereto in the same manner as that just described and is provided with a similar shield 10 for housing the pointed member of the pin, the only difference between the two parts being that in the eye member the hook 3 is omitted and the body of the eye member is provided with a slot 11 to be engaged by the hook 3, the outer side 12 of this member being that which bears against the shoulder 4 of the hook member. 50 In the use of this supporter where used in connection with an ordinary shirt-waist and a skirt the eye member will be pinned to the outside of the waist, as shown in Fig. 1, and the hook member to the inside of the skirt-band. Where this supporter is to be used in connection with a basque worn outside of the skirt, the hook is pinned to the inside of the 55

basque and the eye is pinned to the outside of the skirt-band. At all events the hook member is always to be secured to the skirt-band, so that downward strain applied to the hook from the weight of the skirt or upward strain applied thereto through the eye, caused by any tendency of the waist to rise, will always result in effecting a stable juncture between the hook and the eye. 70

It is to be understood that the members may be made in different sizes to suit the requirements of different cases, and that while I have shown the hook member and the eye member, the one with one hook and the other with one eye, it is to be understood that the hook member may have one or more hooks and the eye member one or more eyes without departing from the spirit or scope of my invention. 80

It will be readily appreciated that when the skirt-supporter is in position it will be concealed from view, so that where used, particularly on ladies' garments, the presentation of an unsightly device at the waist will be effectively obviated. 90

In applying my improved waist and skirt supporter the eye member is secured to the waist in the center of the back above the waist-line, and the hook member is secured inside of the skirt-band at the lower edge of the belt, with the hook turned from the belt, the goods of these two parts of the apparel being crowded in the space formed between the pin and the rib 9, thereby to cause the pin tightly to hug its shield, and thus effect secure locking. The supporter when in this position is invisible, holds the parts firmly assembled, and will not accidentally become disconnected. Further, by reason of its construction the device will not tear, rust, or soil the most delicate fabric, as the materials used in the manufacture are practically non-corrosive. 100

Another important feature of this invention is that it may be employed in lieu of buttons for children's garments and will be found perfectly safe and thoroughly efficient in use. As before pointed out, the supporter is adapted equally for use with a basque as with a waist, its application of the former only requiring the reversing of the hook member and the eye member, the hook member to be secured on the inside of the basque and the eye member on the outside of the skirt-band. 115

It will be readily apparent that when the two members of the hook are in engagement with the waist and skirt they will be held in proper position under all conditions of use. 120

Having thus described the invention, what I claim is—

1. A skirt-supporter comprising a hook member carrying a pin, and formed with a shoulder extending parallel with the pin and with a hook forming a continuation of the shoulder and bent or flexed inward and overlapping the same, and an eye member carrying a pin and provided with a slot to engage

- the hook, the side of the eye member, in use, to bear firmly against the shoulder, and to be held in engagement therewith by the hook and to fill the space between the shoulder and the 5 bend of the hook, the coaction between the side of the eye and the shoulder being such that lateral play will be obviated, thereby to insure positive engagement between the members when locked together.
- 10 2. A skirt - supporter comprising a hook member carrying a pin, and formed with a shoulder extending parallel with the pin and with a hook forming a continuation of the shoulder and bent or flexed inward and over-
- 15 lapping the same, an eye member carrying a pin and provided with a slot to engage the hook, the side of the eye member, in use, to bear firmly against the shoulder, and to be held in engagement therewith by the hook and 20 to fill the space between the shoulder and the
- bend of the hook, the coaction between the side of the eye and the shoulder being such that lateral play will be obviated, thereby to insure positive engagement between the members when locked together, one side of each 25 of the members being cut away to leave a projection at one end, the said projection being bent to form a shield and having arranged parallel to its length, at the cut-away portion, a tubular rib, and a pin having one of its 30 arms suitably secured in the rib, and the pointed free end of the other arm to engage with the shield.
- In testimony that I claim the foregoing as my own I have hereto affixed my signature in 35 the presence of two witnesses.
- ELIZABETH M. ADAMS.
